UNITED STATES PATENT OFFICE.

MAURICE E. BLOOD, OF SYCAMORE, ILLINOIS, ASSIGNOR TO HIMSELF,
CHARLES W. MARSH, AND WILLIAM W. MARSH, OF SAME PLACE.

GRAIN-ADJUSTING DEVICE FOR HARVESTERS.

SPECIFICATION forming part of Letters Patent No. 278,492, dated May 29, 1883.

Application filed October 10, 1882. (No model.)

To all whom it may concern:

Be it known that I, MAURICE E. BLOOD, residing at Sycamore, in the county of De Kalb and State of Illinois, and a citizen of the United States, have invented new and useful Improvements in Grain-Adjusting Devices for Harvesters, of which the following is a full description, reference being had to the accompanying drawings, in which—

10 Figure 1 is a top or plan view, showing a portion of the receiving-platform, binding-table, and frame-work, sufficient to illustrate the location of the parts forming the invention; Fig. 2, a section on line $\alpha\alpha$ of Fig. 1; Figs. 3, 15 4, and 5, details showing the "butter" and its devices set at different inclinations to operate on different lengths of grain.

The object of this invention is to construct and apply improved devices for straightening 20 the grain and delivering it in proper relation to a self-binder for binding purposes, and to improve the means for operating such grain straightening and delivering devices; and its nature consists in the several parts and combination of parts hereinafter described, and set forth as new in the claims.

In the drawings a complete machine is not illustrated, but only so much as is deemed necessary for showing the location and arrangements of the devices which form the subject-matter of this invention.

30 A represents a grain-receiving platform, supported at its front side on a sill, A'', having thereon the ordinary sickle-guard, carrying a sickle, as usual, and having at its rear side a table, A', for binding the grain.

B is a guide-board standing diagonally across the inner forward corner of the platform A, for evening the butts and holding them 40 in place when swept around by a rake, the platform A being intended for use with a platform-rake.

B' B'' are cross-sills, between which the main or drive wheel is located.

45 C C' are reel-posts supporting a reel in the usual manner.

D D' D'' are frame-pieces supporting the binder-operating mechanism, the binding-arm, and other devices, and supported upon suitable posts or uprights, D'.

E is a cross-bar extending from the bar D to the bar D', and supported above such bars, as shown, by brackets E', and, as shown, the bar D is held against strain by a diagonal brace-bar, E''. 55

The parts so far referred to can be of any well-known form of construction and arrangement suitable to furnish a platform for the grain, a table on which the grain can be bound, and a frame-work for the drive-wheel, binding devices, and appliances pertaining to a self-binding harvester.

F is a wheel or disk formed of a rim or outer portion, e, with arms and spokes e' joining the rim to a center, e''. This disk or wheel F has 65 located on its periphery a series of teeth—four, as shown—each having an acting portion, a, and a heel, a', and pivoted between the face of the rim e and an ear, b, so as to be free to swing to project the acting portion into 70 position for use, or drop into position to be out of use while the wheel or disk is rotated.

G is a cam or guide way formed of a segmental flange or rim, d, and arms or spokes d', connecting the flange or rim to a center or hub, 75 d', from which hub extends out another arm or spoke, d''. This cam is arranged in such relation to the periphery of the wheel F and the teeth a as to be engaged in succession by the heels a' of the teeth, and hold their points 80 or acting ends projected to engage the grain and carry it forward, and otherwise act thereon, as hereinafter described.

H is a strip of sheet-iron or other suitable material, having a curved portion to coincide 85 with the curve of the segment or flange G, and connected to such flange by lugs or projections e, extending out from the flange, and to which the strip H is attached by rivets or otherwise. This strip H acts as a retainer to be pressed 90 on the grain at the butt-end and hold the butts back, and also as a guard against the entrance of the grain to the driving gear or devices of the wheel or disk F.

I is a rod of wrought-iron or other suitable 95 material, curved or bent as shown in Figs. 2 and 3, and arranged to lie adjacent to the face of the wheel or disk F on the opposite side to the strip H to come in contact with the grain on that side of the disk, and act as a retainer 100.

for the heads and hold them back. This retainer I is attached, as shown, to the suspending rod or bar for the disk or wheel F, and its extreme free end has a downward curve to cause it to lie in a lower plane than the retainer H when the disk is standing vertical, and have it act to some extent against the travel of the grain.

J is a rod or bar, the lower end of which is pivotally connected by a suitable pin or bolt to an ear, f, on the segment or flange G, and its upper end has a slot, g, for the passage of a rod, J', mounted on the frame-pieces D and E, allowing the bar to slide on such rod and to be turned thereon to change the position of the disk or wheel F, and also its inclination in relation to the platform.

K is a lever, the inner end of which is connected with the pin or bolt attaching the bar J to the ear f, the upper end of which is arranged to be within reach of the driver of the machine. This lever, near its upper end, engages with a rack-bar, K', and by means of this lever the wheel or disk F can be turned to stand at different inclinations, both vertical and horizontal, and when the disk is set at the proper inclination the lever can be locked to the rack-bar K', holding the disk or wheel in its set position. The first effect produced upon the disk by moving the lever K from the center of the rack-bar toward either end is to swing the disk in a horizontal plane and without canting it; but as the swing of the lever is increased—that is, as it is moved nearer the end of the rack-bar—further horizontal swing of the disk will be prevented by reason of edges of the slot g pressing upon opposite sides of the rod J', or, in other words, pinching said rod. Now, if the lever K be still further moved, the effect upon the disk will be to cant it to either of the positions shown in Figs. 4 and 5, dependent upon which way the lever is moved. The feasibility of thus canting the disk is further assured by reason of its weight and the engagement of its teeth with the grain on the platform, and when once canted it will be apparent that the grain will act as a wedge or stop to prevent any tendency of the disk to return to a vertical position, which can only be done by forcing it around with the lever K.

L is a short shaft, on which is mounted the wheel or disk F, and supported by the hub or center of the segment or flange G, in which the shaft has its bearing. This shaft has on one end a beveled pinion, h, which meshes with a corresponding pinion, h', on the end of a shaft, L', the inner end of which is supported in a bearing, i, on the arm or spoke d' of the segment or flange G.

M is a coupling connecting the shaft L' with the driving-shaft.

N is the driving-shaft.

O is a sprocket-wheel on one end of the shaft N, and driven by a chain from the main or drive wheel or other moving part of the binder or machine.

P is a standard, the lower end of which is

bolted or otherwise secured to the cross-beam B', and its upper end provided with a bearing, j, for the shaft N.

The devices or parts represented by the letters J, J', K, K', L, L', M, N, O, and P can be constructed and arranged in some other manner than shown, to suit the style of machine to which the disk or wheel F, cam or segment G, and retainers H and I are to be applied and used, so long as they furnish the means for suspending the disk, cams, and retainers, changing the angle of inclination at which they stand, and driving the wheel or disk. The disk or wheel, with its cam or segment and retainers, is located to have the teeth a engage the butts of the grain at a point in line, or nearly so, with the inner divider or inner guard-finger of the sickle, as shown in Figs. 1 and 2, or in such relation to the platform and grain as will cause it to act on the butts before the grain passes to the binder, and, as shown, a spring-finger, k, is provided to retard the grain at the head end and assist the wheel or disk in straightening oblique-lying grain.

The operation is as follows: The wheel or disk F is turned or swung through the arm or lever K to stand vertical or inclined, as shown in Figs. 3, 4, and 5. When standing as shown in Fig. 3, the teeth a will engage the grain near the butt-end and advance the butts faster than the heads, straightening the grain by carrying the butts forward, and this set of the wheel or disk is the one intended for use with the ordinary cut of grain, which falls on the platform with the heads in advance of the butts. When the heads are considerably in advance of the butts, the wheel or disk is to be swung or turned into the position shown in Fig. 5, raising the retainer H and lowering the retainer I, allowing more space for the free travel of the butts, and producing a retention on the heads by the contact of the retainer I with the grain, holding the heads back and carrying the butts forward; and when the heads are to have a freer travel than the butts the disk or wheel F is swung or turned into the position shown in Fig. 4, raising the retainer I and lowering the retainer H, allowing a free space for the travel of the heads, and producing a pressure on the butts by which they are held back, so that the disk will act to carry the heads forward faster than the butts. This arrangement enables the driver or operator to entirely control the flow of the grain, and to change such flow as required to produce a proper delivery of the grain to the binder.

The devices are very simple, and will do the work in an effectual and reliable manner, and are readily adjusted to act and advance either the butts or the heads, as required, to straighten the grain.

It will be noticed that the swinging of the rim or wheel F to the different positions causes the teeth to act on the grain nearer to or farther from the butts, producing a change in the direction of the flow, as well as straightening it, so that the grain can be delivered in

proper relation to the binder for binding purposes.

The retainers *k* are secured to the face of the platform, as shown in Figs. 1 and 2, and are curved upward and have a spring or yielding movement, which will allow the grain to pass readily, and at the same time form a stop or resistance by which the heads will be retarded, and these springs or retainers could 10 be applied and used with some other form of device than the disk or wheel *F*.

The retainer *H* will always be necessary where the butts only are retarded or held back, and where the heads only are to be retarded 15 or held back the retainer *I* is all that need be used; but, as in the handling of grain either end is liable to be the one to be operated upon, it is preferred to use both retainers, as shown and described.

20 The wheel or disk *F*, with the retainers *H* and *I*, is supported from the cross-rod *J'* through the medium of the suspending-bar *J*, the lower end of which is connected with the frame or camway *G*, and the upper end of which is provided with an elongated slot, so that the wheel *F*, with the frame *G* and the retainers *H* and *I*, can turn to the right or left, as represented in Figs. 4 and 5. The driving-shaft *L'* does not interfere with the movements mentioned, 25 by reason of the provision of the universal coupling *M*, which permits the forward end of the shaft to swing to the right or left with the adjuster. The swinging movements of the adjuster to the positions represented in Figs.

4 and 5 are effected by means of the inclined 35 lever *K*, which has its inner end connected with the frame *G* by a pin, so that by swinging the outer end of the lever the adjuster will be canted the same as though the lever stood in a vertical position, the adjuster turning on the 40 coupling *M* and rod *J'* as the pivotal points.

What I claim as new, and desire to secure by Letters Patent, is—

1. A rotary disk or wheel arranged to operate on the grain, and provided with a retainer, 45 *H*, adapted to be brought into contact with the grain at the butts, substantially as and for the purposes specified.

2. A rotary wheel or disk arranged to engage the grain, and provided with a retainer, 50 *I*, adapted to be brought into contact with the grain at the heads, substantially as and for the purposes specified.

3. A rotary wheel or disk arranged to engage the grain, and provided with retainers 55 *H* *I*, adapted to be brought into contact with the grain on either side of the disk or wheel, substantially as and for the purposes specified.

4. A rotary wheel or disk, *F*, having teeth to engage the grain, and a cam or guide way, 60 *G*, in combination with the retainers *H* *I* and suspending-rod *J*, for operating on the grain, substantially as and for the purposes specified.
